[57] **CLAIM**

I claim the ornamental design for tree holder, as shown and described.

DESCRIPTION

FIG. 1, is the front elevation of the tree holder.

FIG. 2, is the top view of the tree holder.

FIG. 3, is the left side elevation of the tree holder.

FIG. 4, is the rear elevation of the tree holder; and,

FIG. 5, is the right elevation of the tree holder.

The broken line showing in FIG. 1 is for illustrative purposes only and forms no part of the claimed design.
